UNITED STATES PATENT OFFICE.

GEORGE S. ANDREWS, OF BUTLER, PENNSYLVANIA.

GAS-BURNER.

No. 864,593.

Specification of Letters Patent.

Patented Aug. 27, 1907.

Application filed December 26, 1906. Serial No. 349,566.

To all whom it may concern:

Be it known that I, GEORGE S. ANDREWS, a citizen of the United States, and a resident of Butler, in the county of Butler and State of Pennsylvania, have invented a new and Improved Gas-Burner, of which the following is a full, clear, and exact description.

This invention relates to certain improvements in incandescent gas burners, and relates more particularly to the construction and means for supporting the various parts going to make up said burners.

The object of the invention is to so construct and connect the various parts that any of them may be removed for the purpose of cleaning or to permit the insertion of new parts without interfering with or removing the adjacent and coacting parts.

More specifically, the object of my invention is to provide means whereby the mixing tube may be removed independent of the base mantle, and whereby the mantle may be removed independent of the globe or shade.

The invention consists in certain features of construction and combination of parts, all of which will be fully set forth hereinafter and particularly pointed out in the claims.

Reference is to be had to the accompanying drawings forming a part of this specification, in which similar characters of reference indicate corresponding parts in all the figures, in which

Figure 1 is a perspective view of a device embodying my invention; Fig. 2 is a plan view, the upper portion of the device being broken away; Fig. 3 is a vertical longitudinal section; Fig. 4 is a view similar to Fig. 3, but showing the gas delivery nipple moved out of the path of the mixing tube and mantle support, the latter being partially removed; Fig. 5 is a sectional detail showing the means for securing certain parts together; Fig. 6 is a vertical longitudinal section through a modified form of mixing tube; Fig. 7 is a side elevation showing a modified construction for permitting the removal of the gas delivery nipple from the downward path of the mixing tube and mantle support; and Fig. 8 is a vertical section on the line 8—8 of Fig. 7.

In connection with my improved gas burner, I provide a fixture comprising a gas delivery conduit 10 of any suitable character and supported in any suitable manner. Carried by this conduit are two separate and independent parts, one of which, the upper, comprises the mixing tube, the mantle support and the globe or shade support, while the other, the lower, comprises the gas delivery conduit, the delivery nipple and means whereby the quantity of air admitted to the mixing tube may be regulated.

To facilitate the separation of the various members of the upper part, I construct either one or both of the parts movable in respect to the other.

In the specific form of my invention which I have illustrated in the drawings, the lower part, namely, that comprising the gas delivery conduit, the delivery nipple and the air regulator, is movable from beneath the upper part, whereby the various members comprising the upper part may be removed from the under side thereof. The lower part may be secured to the fixture in any suitable manner and be made movable in respect thereto by means of various different constructions.

In Figs. 1, 2, 4 and 5 I have illustrated the lower part as comprising a curved gas delivery conduit 11, rigidly secured to the end of a turning plug 12 mounted to rotate within a head 13 rigidly secured to the fixture 10. Within the head is also mounted a turning plug or cock 14, by means of which the flow of gas from the fixture to the delivery conduit 11 may be normally controlled. The turning plug 12 is preferably conical in form and held in place in any suitable manner, as, for instance, by a screw bolt 15 and washer 16. The axis of the turning plug is preferably in a vertical line, and the conduit 11 is secured to the lower open end of the turning plug. The conduit 11 carries on its lower or outer end a head 17 having a passage therethrough communicating with said gas delivery conduit and provided, if desired, with a small turning plug or cock 18. The head 17 terminates in an upwardly directed gas delivery nipple 19 adapted to direct the flow of the combustible gas to the center of the mixing tube supported directly above the same but independently thereof. As the turning plug 12 is freely rotatable within the head 13 and as the conduit 11 leading from the bottom thereof is curved outward, it is evident that the delivery end of the conduit, or in other words, the nipple 19, may be moved in a lateral direction to bring it entirely out from beneath the mixing tube and the remainder of the burner. For limiting the position of the nipple 19 and insuring the positioning of said nipple directly below the center of the mixing tube, I may provide any suitable stop or projection operating in conjunction with the turning plug 12. This may, if desired, take the form of a small screw 20 carried by the head 13 and engaging with stops on the plug 12. In order to bring the gas delivery nipple 19 out from beneath the remaining parts of the burner, it is evident that it may be moved in other directions than in a horizontal one.

In Figs. 7 and 8 a slightly modified form of construction is disclosed in which the turning plug 12^a within the head 13^a has its axis in a horizontal rather than a vertical line. The gas delivery conduit 11^a secured to said turning plug is curved so as to bring the head 17 and delivery nipple 19 directly below the mixing tube as in the form first described, but in order to move the

delivery nipple from beneath the other parts of the burner, it is moved downward and backward, as indicated in dotted lines in Fig. 7. It is evident that the conduit 11^a and turning plug 12^a may be of various forms, it only being essential that the nipple 19 be normally supported directly below the center of the mixing tube and entirely independent thereof and be movable to a position out from beneath said tube, whereby the latter may be moved downward to separate it from the parts which normally support the same.

Supported by the head 13 of the fixture 10 and entirely independent of the members constituting what has been designated "the lower part" is means for supporting the mantle, mixing tube and globe or shade. This means preferably takes the form of a ring 21 carried by an arm 22 preferably secured to the top or upper surface of said head. As shown, the arm is rigidly secured by means of screws 23, but it is evident that one of these screws may, if desired, be removed and the ring 21 moved laterally about the other screw as a pivot.

Secured to the outer surface of the ring 21 are a plurality of rests or supports 24 for any suitable form of globe or shade, not shown, and extending through the ring and supported upon the inner surface thereof is a shell 25 serving to carry the mixing tube and indirectly support the mantle. The shell 25 preferably comprises a cylindrical portion 26 adapted to fit the inner surface of the ring 21, and is provided with a bead or flange 27 to limit the upward movement of said shell through said ring. For securing the shell within the ring 21, I provide either the ring 21 or the cylindrical portion 26 of the shell with a bayonet slot 28. Preferably this slot is in the cylindrical portion 26 and coacts with projections extending inward from the surface of the ring 21. In the construction illustrated, this projection takes the form of a small screw 29 having a washer 30 rigidly secured to the inner end thereof. By moving the shell upward in the ring 21 and then slightly rotating the shell, the screw 29 may be brought to the inner end of the slot 28. By then turning the screw to draw the washer 30 into firm engagement with the inner surface of the ring 26, the two parts may be held firmly in engagement with each other and liability of their accidental separation rendered impossible.

Extending upward from the ring 26 and integral therewith are a plurality of bars or legs 31 connected at their upper ends to a tube 32. This tube serves as a guide for the upper end of the mixing tube which extends therethrough, and also serves as a support for the ring 33 of the mantle. The tube 32 is provided with a flange or shoulder 34 to limit the downward movement of the ring 33, and the latter carries outwardly projecting arms 35 supporting a wire 36 from which the mantle 37 is suspended, the lower end of said mantle being in engagement with the upper end of the ring 33.

Within the shell 25 and extending upward from the lower end thereof to the inside of the mantle 37, is the mixing tube 38. This tube is preferably cylindrical in form and at its lower end engages with and is supported by the lower end of the shell. The shell

preferably terminates in a cylindrical flange 39 fitting 65 the outer side of the tube, and means are provided, as, for instance, a set screw 40, for holding the mixing tube within the flange 39. The lower end of the mixing tube is provided with an annular flange 41 engaging with the lower end of the shell and serving to 70 limit the upward movement of said tube. The upper end of the mixing tube extends through the tube 32 and terminates adjacent the lower end of the mantle 37, said upper end of the tube supporting a screen 42 held in place in any suitable manner but preferably 75 by engagement with the inner surface of an outwardly directed bead 43.

The mixing tube is preferably of the form illustrated in Figs. 1, 3 and 4, but various modified forms of construction may be employed. In Fig. 6 one of such 80 modifications is illustrated, wherein the mixing tube 38^a is supported upon the outwardly directed flange 44 of a supporting collar 45, which collar is secured to the flange 39 of the shell and also serves to support a screen 46 by means of suitable wire standards 47. In each case the lower end of the mixing tube is entirely open to the atmosphere, and when in use is supported directly above the delivery end of the nipple 19. The gas escaping from said nipple passes upward through the mixing tube and air is admitted from the outside to 90 become thoroughly mixed as the two pass upward through the tube. The mixture is ignited upon the upper surface of the screen 42, and the intense heat produced at this point serves to render the mantle 95 luminous. In order to regulate the quantity of air entering the lower end of the tube, I provide the nipple 19 with an air regulator 48, preferably in the form of an inverted cone screw-threaded upon said nipple. By rotating this cone, the distance between its outer edge and the lower end of the mixing tube may be controlled 100 at will and the size of the air inlet opening readily regulated. The air regulator and the mixing tube are supported entirely independently of each other, and thus the space between the two is left free and unrestricted, but, at the same time, capable of being readily 105 controlled.

The improved construction above described possesses very many advantages over those devices commonly employed.

When it is desired to remove the mixing tube to 110 clean or replace the screen 42 or for any other purpose, it is entirely unnecessary to remove the globe, shade, mantle, or any other part, save the gas delivery nipple. This may be readily swung either to one side or downward, as shown in Figs. 7 and 8, and by loosening the 115 screw 40 the mixing tube may be readily removed from the lower end of the shell. The support for the mantle may be likewise removed without disturbing the shade or globe resting on the supports 24, and this is accomplished by merely loosening the screws 29 120 and rotating the shell 25 to unlock the bayonet joint. The shell carrying the mixing tube and mantle may then be separated from the remaining parts by moving it downward through the supporting ring 21, as indicated in Fig. 4. This permits of the removal of the broken 125 mantle and the insertion of a new one in a very short space of time and without taking the entire device apart.

Having thus described my invention, I claim as new and desire to secure by Letters Patent:

1. A gas burner, comprising a plurality of parts, one of said parts including a supporting ring, a shell detachably secured thereto, and a longitudinally movable mixing tube detachably secured to said shell, and the other of said parts including a gas delivery nipple, one of said parts being movable in respect to the other to bring the mixing tube and delivery nipple out of alignment and permit the removal of the tube or the shell. 80
2. A gas burner, comprising a plurality of parts, one of said parts including a supporting shell, and a mixing tube having one end thereof detachably secured to said shell adjacent one end of the latter, and the other of said parts including a gas delivery nipple, one of said parts being movable in respect to the other to permit the longitudinal movement of the mixing tube. 85
3. A gas burner, comprising a supporting ring, a shell detachably secured thereto and removable from the under side thereof, a mixing tube detachably secured to said shell and removable from the under side of the latter, and a gas delivery nipple normally supported in alignment with the mixing tube but movable out of alignment therewith to permit the removal of the tube or the shell. 90
4. A gas burner, comprising a supporting ring, a shell detachably secured thereto, a mixing tube carried by said shell, and a gas delivery nipple normally supported in alignment with the tube but movable out of alignment therewith to permit the longitudinal movement and removal of the shell and tube. 95
5. A gas burner, comprising a plurality of parts supported independently of each other, one of said parts including a supporting member, a shell detachably secured thereto, a mixing tube carried by said shell, and a gas delivery nipple normally supported in alignment with said tube, one of said parts being movable in respect to the other to bring the mixing tube and nipple out of alignment. 100
6. A gas burner, comprising a plurality of parts supported entirely independently of each other, one of said parts including a longitudinally movable mixing tube and the other of said parts including a gas delivery nipple and an air regulator, one of said parts being laterally movable so as to bring the mixing tube and delivery nipple out of alignment and permit the longitudinal movement of the mixing tube, and the air regulator being longitudinally movable in respect to the nipple and mixing tube to control the size of the inlet to the latter. 105
7. A gas burner, comprising an upper part including a mixing tube, a mantle and a mantle support, and a lower part comprising a gas delivery conduit, a delivery nipple carried thereby and supported directly below the mixing tube but entirely independently thereof and an air regulator, said lower part being movable in respect to the upper part to bring the delivery nipple out of alignment with the mixing tube, and said air regulator being independently movable in respect to said mixing tube. 110
8. A gas burner, comprising an upper part including a mixing tube, mantle and a mantle support, a lower part comprising a gas delivery conduit, a delivery nipple supported directly below the mixing tube but entirely independent thereof, said lower part being laterally movable in respect to the upper part, and means whereby the lateral movement of said lower part controls the supply of gas thereto. 115
9. A gas burner, comprising a plurality of parts supported independently of each other, one of said parts including a mixing tube and the other of said parts including a gas delivery nipple normally supported in alignment with said mixing tube, and means whereby the movement of one of said parts to bring the delivery nipple and mixing tube out of alignment shuts-off the supply of gas to said nipple. 120
10. A gas burner, comprising a plurality of parts supported independently of each other, one of said parts including a longitudinally movable mixing tube and the other of said parts including a gas delivery nipple, one of said parts being movable to bring the delivery nipple and
- mixing tube out of alignment and permit the removal of the mixing tube, and means whereby said movement of one of the parts controls the supply of gas to said delivery nipple. 125
11. A gas burner, comprising an upper part and a lower part, one of said parts being movable in respect to the other, the said upper part comprising a supporting ring, a mixing tube, a mantle, and a mantle support, and the said lower part comprising a gas delivery conduit, a delivery nipple and an air regulator, said nipple and regulator being supported directly below the end of the mixing tube but independently thereof. 130
12. A gas burner, comprising an upper part and a lower part, one of said parts being laterally movable in respect to the other, the said upper part comprising a supporting ring, a mixing tube, a mantle, and a mantle support, and the said lower part comprising a gas delivery conduit, a delivery nipple and an air regulator, said nipple and regulator being supported directly below the end of the mixing tube but independently thereof. 135
13. A gas burner, comprising an upper part, including a stationary supporting ring, a mixing tube supported thereby and removable from the lower side thereof, and a lower part, including a gas delivery nipple supported directly below said mixing tube and movable out of the downward path of said mixing tube. 140
14. A gas burner, comprising an upper part, including a stationary supporting ring, a mantle and mantle support, a member carried by said ring and carrying said mantle and mantle support, said member being detachably connected to said ring and removable from the lower side thereof, and a lower part, including a gas delivery nipple supported directly below said member but independently thereof and movable out of the downward path of said member. 145
15. A gas burner, comprising an upper part, including a supporting ring, a shell carried thereby, a mantle support, and a mixing tube carried by said shell, said shell being downwardly removable in respect to said ring, and said mixing tube being downwardly movable in respect to said shell, and a lower part, including a gas delivery nipple supported directly below said mixing tube but independently thereof, one of said parts being movable in respect to the other, whereby the shell or mixing tube may be removed from the supporting ring. 150
16. A gas burner, comprising an upper part, including a supporting ring, a shell carried thereby, a mantle support, and a mixing tube carried by said shell, said shell being downwardly removable in respect to said ring, and said mixing tube being downwardly movable in respect to said shell, and a lower part, including a gas delivery nipple supported directly below said mixing tube but independently thereof, said lower part being movable in respect to the upper part, whereby the shell or mixing tube may be removed from the supporting ring. 155
17. A gas burner, comprising an upper part, including a supporting ring, a shell carried thereby, a mantle support, and a mixing tube carried by said shell, said shell being downwardly removable in respect to said ring, and said mixing tube being downwardly movable in respect to said shell, and a lower part, including a gas delivery nipple supported directly below said mixing tube but independently thereof, said lower part being laterally movable out of the path of the downward movement of the shell and mixing tube. 160
18. A gas burner, comprising a supporting ring, a mixing tube supported within said ring, a gas delivery nipple supported directly below said mixing tube but entirely independently thereof, and means carried by said nipple and longitudinally movable in relation thereto for controlling the size of the air inlet opening to said mixing tube. 165
19. A gas burner, comprising a mixing tube, a mantle and mantle support adjacent the upper end thereof, means for supporting said mixing tube, whereby it may be removed from beneath the mantle and mantle support, a gas delivery nipple supported directly below said mixing tube, means whereby the nipple may be moved out of the downward path of said mixing tube, and an air regulator

carried by said nipple and coöperating with the lower part of said mixing tube for controlling the air inlet opening thereto.

20. A gas burner, comprising an open-ended mixing tube, a gas delivery nipple normally supported directly below said tube but movable out of alignment therewith, and an air regulator comprising a conical disk carried by said nipple and movable longitudinally thereof for closing or partially closing the end of the mixing tube.

10 21. In combination, a fixture, a turning plug mounted therein, a gas delivery conduit rigidly secured to said turning plug, a gas delivery nipple carried by said conduit, a supporting nipple carried by said conduit, a supporting ring rigidly secured to said fixture, a shell carried by said ring and downwardly removable therefrom, a mixing tube carried by said shell and downwardly removable therefrom, a mantle support and mantle carried by said shell adjacent the upper end of said mixing tube, a screen carried by the upper end of said mixing tube, and an air regulator carried by said nipple independently of the mixing tube but relatively movable in respect thereto.

22. A gas burner, comprising an annular support, a shell carried by and extending through said support and removable from the under side thereof, said shell and support being provided with bayonet connections for securing them together, and locking means for preventing the accidental displacement of the shell.

23. In combination, a supporting ring, a shell extending through said ring and having a cylindrical surface in contact therewith, said shell being provided with bayonet slots adjacent said ring, and screw studs extending inward, from said ring and adapted to pass through said slots, said screw studs being provided with enlarged inner ends adapted to contact with the inner surface of the shell and prevent accidental unlocking of the bayonet joint.

30 24. A gas burner, comprising a supporting ring, a shell extending through said ring and having a cylindrical surface in contact therewith, a bead on said shell adapted to contact with the lower edge of the ring and limit the upward movement of the shell, said shell being provided with 40 bayonet slots in its cylindrical portion, screw studs carried by said ring and adapted to engage in the bayonet slots of the shell for supporting the latter, washers secured to the inner ends of said screw studs and adapted to contact with the inner surface of the shell for preventing 45 the accidental unlocking of the bayonet connections, and a mixing tube detachably secured to said shell and removable from the under side thereof.

40 In testimony whereof I have signed my name to this specification in the presence of two subscribing witnesses.

50 GEORGE S. ANDREWS.
